MAIL BOX

Filed May 8, 1931

Inventor.

Edward Wm Bowers,
by Walter P. Geiger
Attorney.

UNITED STATES PATENT OFFICE

EDWARD W. BOWERS, OF MEDINA, NEW YORK

MAIL BOX

Application filed May 8, 1931. Serial No. 535,917.

This invention relates to improvements in mail boxes, and more particularly to mail boxes of the type intended for use in rural communities.

5 One of its objects is to provide a simple, inexpensive and practical box of this character having means for indicating to the mail carrier that there may or may not be contents in the box, thereby saving him considerable time in collecting the mail along his route.

10 A further object of the invention is to provide compact and effective means for restoring the indicator to an inoperative or non-display position after the closure of the box has been opened by the carrier for removing its contents.

In the accompanying drawing:—

Figure 1 is a perspective view of a mail box embodying my invention. Figure 2 is a longitudinal section thereof, showing in full lines the indicator and associated parts in its display position, and by dotted lines its non-display position. Figure 3 is a cross section taken in the plane of line 3—3, Figure 2. Figure 4 is a fragmentary section showing the lock.

Similar characters of reference indicate corresponding parts throughout the several views.

30 In the preferred embodiment of my invention shown in the drawing, the same consists of a suitable box 10, of any desired shape or dimensions, supported on a post 11 and open at its front end to permit access to the interior of the box. Extending over this opening, is a movable closure or cover 12, which may be curved or arcuate in shape, as shown, and is mounted for vertically-swinging movement to assume either of the positions shown 35 by full and dotted lines in Figure 2.

The preferred means for mounting the closure 12 to swing vertically consist of side arms 13 pivoted at 14 to opposite sides of the box, the front ends of these arms being joined to the closure in any appropriate manner. At their rear ends, these arms are connected to depending links 15 pivoted at their lower ends to a vertically-swinging yoke or closure-actuating member 16 pivoted at its rear end, 45 as indicated at 17, to opposite sides of the

box. Projecting from the front end of the yoke 16 is a suitable handle 18. Stop lugs 19 depend from the box 10 adjacent its front end and are arranged in the path of movement of the cover-actuating yoke 16 to limit 55 its downwardly-swinging movement or the position corresponding to the fully open position of the closure 12. By this construction, when the yoke 16 is swung from the full to the dotted line position shown in Figure 2, 60 the arms 13 are swung in a direction to elevate or open the closure, permitting access to the box for the removal of its contents. In practice, a lock is employed for locking the closure. 65

For the purpose of indicating to the carrier or collector of mail that given box contains mail to be picked up, I employ an indicator or signal element which is adapted to be set by the party placing mail in the box 70 and which is adapted to be automatically shifted to a non-display position at the time the mail is picked up by the carrier. To this end, I employ a suitable indicating element 75 20 carried by a rocked shaft or hinge pintle 21 journaled in brackets 22 adjacent to the lower front side of the box, this element being suitably characterized so that it is clearly visible by the carrier when approaching the box. A counterweight 23 or equivalent element is applied to the indicator for normally holding it in an elevated inoperative position against the under side of the box, as shown by dotted lines in Figures 2 and 3. In order 80 to hold the indicator in its pendant display position, the same is provided with a projection or catch 24 which is adapted to be inserted in a corresponding notch 25 in one of the bearing brackets 22. The pintle 21, 85 to which the indicator is attached is slidably fitted in the bearing bracket and the catch 24 is interlocked with the notch 25 by shifting the indicator toward the bracket to the position seen by full lines in Figure 2. By 90 shifting the pintle 21 rearwardly, the indicator catch 24 is released from its locking notch 25 and the indicator thereupon is shifted by its counterweight to a non-display 95 position against the under side of the box 10. In order to automatically effect the re- 100

lease of the indicator to its non-display position, I provide the pintle 21 with an extension 26 which is arranged in the path of movement of the yoke 16, so that upon depressing the yoke to open the closure 12 and remove the contents of the box, the yoke, which has a cam face 27 thereon, trips the pintle extension to unlatch the indicator 20.

To protect the contents of the box from the weather, the closure 12 is provided along its marginal side edges with flanges 28 which overlap the adjoining sides of the box. At its top edge the closure terminates in a curved lip or flange 29 arranged to engage a companion reversely-bent lip or flange 30 on the box and along the upper end of its opening.

While any suitable means may be employed for locking the closure 12, that shown in the drawing, by way of example, consists of a padlock 31 which engages a bracket 32 secured adjacent to the lower side of the closure and the cross bar of the yoke 16 in the manner shown in Figure 4, whereby both the closure and the yoke are securely fastened against actuation by malicious persons.

It is to be understood that various modifications in the construction and arrangement of parts may be made without departing from the spirit of the invention, and I do not, therefore, wish to be limited to the exact construction herein shown and described.

I claim as my invention:—

1. A device of the character described, comprising a box having an opening therein, a movable closure therefor, a combined swinging and longitudinally movable signaling element including means for normally urging it to a non-display position, means for latching said element against swinging movement in a display position, and means controlled by the movement of said closure in one direction for automatically shifting said signaling element longitudinally for releasing said latching means.

45 2. A device of the character described, comprising a box having an opening therein, a movable closure therefor, a swinging signaling element mounted on one of the box-walls to swing toward and from the same and shiftable along its axis and including means for normally urging it to a non-display position, means for latching said element in a display position, and means controlled by the movement of said closure in one direction for shifting the signaling element along its axis for releasing it from said latching means.

3. A device of the character described, comprising a box having an opening at its front end, a movable closure therefor, a signaling element arranged to assume a display and a non-display position, a combined rotatable and longitudinally shiftable member for said signaling element mounted on said box, means for latching said shiftable member against rotary movement in a sig-

nal displaying position, and means actuated by movement of the closure in one direction for shifting said signal-bearing member longitudinally and releasing the same from said latching means and effecting the rotation of said member to bring its signaling element into a non-display position.

4. A device of the character described, comprising a box having an opening therein, a movable closure therefor, a trip member connected to said closure, and a signaling element applied to the box and including an axially-shiftable pintle disposed parallel to the box-wall to which it is applied, means for latching the pintle against rotation in the display position of the signaling element, said pintle having a part arranged in the path of travel of said trip member for automatically unlatching it during the opening movement of said closure.

EDWARD WM. BOWERS.
